PROCESS FOR THE NITRATION OF AROMATIC HYDROCARBONS

James B. Castner, Woodbury, N. J., assignor to E. I. du Pont de Nemours & Company, Wilmington, Del., a corporation of Delaware

No Drawing. Application September 8, 1932, Serial No. 632,183

12 Claims. (Cl. 260—142)

This invention relates to a new process for the nitration of aromatic hydrocarbons and more particularly to the production of the lower nitro-derivatives of such hydrocarbons by the action of a nitrating acid having a relatively low content of nitric acid.

The aromatic hydrocarbons have, in general, the property of being capable of several stages of nitration by the attachment of 1, 2, or 3 nitro groups directly to the carbon elements of the ring. Benzene, toluene, xylene, and naphthalene are examples of such hydrocarbons, from which the mono, di, and tri nitrocompounds may be prepared. In the nitration of many of the above hydrocarbons it is customary to use as nitrating acids so-called mixed acids, consisting of mixtures of sulfuric and nitric acids. In such mixtures, the sulfuric acid acts, in general, as a dehydrating agent, while the nitric acid brings about the nitration. The degree of nitration depends on the composition of the mixed acid, its content of nitric acid, and the relative proportions of the hydrocarbon and acids present.

An object of my invention is an improved process for the production of the lower-nitro-derivatives of the aromatic hydrocarbons. A further object is such a process in which the nitration of the hydrocarbons is brought about by a nitrating acid having a lower content of nitric acid than has been used heretofore. A still further object is such a process for the production of a nitrotoluene. Further objects will appear as the invention is further disclosed hereinafter.

I have found that a satisfactory process for the production of the lower nitro-derivatives of the aromatic hydrocarbons results, if the nitrating acid has a relatively low nitric acid content. While such an acid may be prepared by a simple mixture of the proper proportions of sulfuric and nitric acids, I find that nitroglycerin spent acid, (i. e., the acid remaining after the nitration of glycerin) is very satisfactory for my process. Such nitroglycerin spent acids are available in large quantities at all high explosive plants, and an average composition for a spent acid of this nature may be taken as 75% total H_2SO_4 , 8.5% total HNO_3 , and 16.5% H_2O .

While various aromatic hydrocarbons are satisfactory for employment according to my invention, such as benzene, toluene, xylene, naphthalene and the like, I find toluene particularly well adapted for the process. Using an acid such as nitroglycerin spent acid, with its low nitric acid content, I find mononitrotoluene to be produced with satisfactory yield, if the proper amounts of

toluene and spent acid are used. After nitration, the nitrotoluene may be separated from the acid by various means, for example, by dilution of the mixture with water to the point where the nitrated product is insoluble.

Toluene has a particular advantage in my process when nitroglycerin spent acid is used, since the toluene serves to denitrate the acid and to strip it of its nitric content almost completely. While I have found the most desirable results to ensue when mononitrotoluene is obtained as the product, dinitrotoluene may also be prepared, particularly if the process is carried out in two stages where the mononitro derivative is the principal product of the first stage. Under certain conditions also, it is satisfactory to produce a mixture of mono- and the dinitrotoluene. It will therefore be apparent that my process has great economic advantages, since it allows the use of a low priced waste acid that is available in large quantities in explosive plants, and brings about the denitration of the waste acid at the same time, a procedure which ordinarily has to be carried out by other and less profitable methods.

When toluene or other aromatic hydrocarbon is nitrated by the process just described, the resulting nitrocompound may contain a certain amount of dissolved nitroglycerin extracted from the acid. The nitrotoluene and any nitroglycerin present after separation from the acid mixture, are washed with water until completely neutral. For the purpose of my invention, the presence of a small amount of nitroglycerin in the nitrotoluene is not only no disadvantage, but is, in fact, an advantage, since this nitrotoluene may be used with satisfactory results as an addition to nitroglycerin for use in dynamites, to improve the freezing properties of the explosive and to bring about other advantages.

As a specific example of the practical adaptation of my process, 500 lbs. of nitroglycerin spent acid, having a composition of approximately 75% total H_2SO_4 , 8.0% total HNO_3 or expressed more nearly according to actual composition 75% H_2SO_4 , 6.0% HNO_3 , 16.5% H_2O and 2.5% nitroglycerin are run into a suitable nitrating vessel. 58 lbs. of toluene are then introduced gradually into the acid with agitation, and cooled, care being taken that an excessive rise of temperature does not result, i. e., not above 140° F. After 30 minutes agitation, the charge is diluted with approximately 75 lbs. of water. The charge is removed from the nitrator and the nitrated material allowed to separate from the acid. The mononitrotoluene is agitated and washed first

with hot water, then with sodium bicarbonate solution, and finally with water. The material is then ready for use as desired.

In the carrying out of my process, it should be understood that many variations in details may be introduced, if desired. While I have described my invention with reference to nitroglycerin spent acids, it is equally applicable to the spent acids resulting from the nitration of other aliphatic alcohols containing at least two hydroxyl groups, such, for example, as ethylene glycol. By the term nitroglycerin, I wish to include not only that compound by itself, but the solutions in nitroglycerin of the commonly used freezing point depressants, such as ethylene glycol dinitrate, nitrated polymerized glycerin, nitrated sugars, nitrochlorhydrins and the like. It is to be understood that I am to be limited only as indicated by the following patent claims.

20 I claim:

1. The process of producing a nitrated aromatic hydrocarbon having a small content of a nitrate of an aliphatic alcohol which comprises nitrating an aromatic hydrocarbon with a spent acid resulting from the nitration of an aliphatic alcohol containing at least two hydroxy groups and recovering the nitrated hydrocarbon along with the aliphatic alcohol as a single product.

2. The process of claim 1, in which the nitration is carried out by means of spent acid resulting from the nitration of glycerin.

3. The process of claim 1, in which the aromatic hydrocarbon is benzene.

4. The process of claim 1, in which the aromatic hydrocarbon is xylene.

5. The process of claim 1, in which the aromatic hydrocarbon is toluene.

6. A process which comprises the nitration of toluene with a spent acid resulting from the nitration of glycerin, diluting the acid solution of

the nitrocompound with water, and separating from the diluted acid solution the nitrated product together with the nitroglycerin recovered from the spent acid.

7. A process for the production of a mononitrotoluene containing a small content of nitroglycerin which comprises the nitration of toluene with a spent acid resulting from the nitration of glycerin, and recovering the nitrated toluene along with the nitroglycerin as a single product. 5

8. A process for the production of a mononitrotoluene which comprises the nitration of toluene with a spent acid resulting from the nitration of glycerin, diluting the acid solution of nitrocompound with water, and separating the nitrated product together with nitroglycerin recovered from the spent acid. 10

9. A process for the production of dinitrotoluene which comprises the nitration of toluene with a spent acid resulting from the nitration of glycerin, and recovering the nitrated toluene along with the nitroglycerin as a single product. 20

10. A process for the denitration of nitroglycerin spent acid which comprises the addition of an aromatic hydrocarbon thereto, and subsequently separating and recovering the nitrated hydrocarbon along with the nitroglycerin as a single product. 25

11. A process for the denitration of nitroglycerin spent acid which comprises the addition of toluene thereto and subsequently separating and recovering at least one of the nitrated derivatives of toluene along with the nitroglycerin as a single product. 30

12. A process for the denitration of nitroglycerin spent acid which comprises the addition of toluene thereto and subsequently separating and recovering mononitrotoluene along with the nitroglycerin as a single product. 35
